UNITED STATES PATENT OFFICE.

JOHN A. BOWYER, OF LA PORTE, INDIANA, ASSIGNOR, BY MESNE ASSIGNMENT, OF ONE-HALF TO JAMES O'BRIEN AND FRANK E. OSBORN.

TELLURIAN.

SPECIFICATION forming part of Letters Patent No. 249,739, dated November 22, 1881.

Application filed April 12, 1881. (No model.)

To all whom it may concern:

Be it known that I, JOHN A. BOWYER, of La Porte, in the county of La Porte and State of Indiana, have invented certain new and useful Improvements in Tellurians, of which the following is a specification.

This invention relates to certain improvements upon the tellurian patented to me on the 5th of April, 1881, in Patent No. 239,644; and it consists in the novel features hereinafter described and claimed.

In the drawings accompanying this specification, Figure 1 is a side elevation of a tellurian embodying my present invention. Fig. 2 is a central vertical section of a joint of the part thereof to which the invention relates.

A represents the base-piece or pedestal upon which the whole mechanism is mounted.

B is the arm upon which the earth-globe b 20 is mounted, provided with a socket, a, fitting the pedestal-pivot, so the arm may revolve upon the same.

The direction of the sun is represented by the needle c, secured to the upright shaft C, 25 secured in the socket a. The earth-axis D is secured to the arm d, which is held in the spindle d', working in a hollowsleeve secured to the arm B.

d³ is a band passing around the pulley d⁴, 30 rigidly fixed to the pedestal and the pulley d⁵ on the spindle d'.

E represents the ecliptic, supported on the curved arm E', secured by the clamp-screw E² to the slotted bracket E³, which extends from 35 the sleeve, already mentioned, embracing the spindle d'.

The parts above described correspond with the same parts in my said patent of April 5, 1881.

40 G is the moon-globe, vertically adjustable upon a rod, g², stationarily held upon the sleeve g⁴ upon the end of a horizontal arm, g, mounted upon and revolving about the said sleeve upon the spindle d'. The rod g² is bent into rectangular form, and its point is stepped in the bend of another upright rod, g', secured in a 45 socket in the upper end of the spindle g³. At the lower end of this spindle is a pulley, g⁷,

which a band, g⁶, passing around it and pulley g⁵, rigidly secured to said sleeve upon the spindle d', actuates as the arm g and the parts carried upon it are swung around the earth.

Upon the rod g' is adjustably secured a hemispherical shield, H, conforming in dimension to the moon's surface, and located so as to 55 cover one-half thereof at all times, it being intended that like changes in the vertical adjustments shall be made of both moon and shield. This shield rotates around the moon as the latter is swung on the arm g, and it is intended 60 to represent the side of the moon illuminated by the sun, and to change position as the two planets change relatively, keeping its face at all times turned toward the sun, and thus exhibit the different phases of the moon. At the same 65 time, by the construction shown, the moon-globe presents the same side at all times to the earth, and I am thus enabled to illustrate another peculiarity of these bodies. By making the bend in the rod g' short it becomes 70 possible for the shield and its support to pass through the bend of the rod supporting the moon.

L is a pointer for indicating the earth's position upon the dial upon the base-piece, and 75 K is a compass indicating the direction of the north pole, substantially as in my former patent.

I am aware that non-rotating shields accompanying and representing the darkened 80 half of earth-globes, which were revoluble at pleasure by hand, have been used, and such combination of the shield with a globe I do not claim.

I claim—
85 In a tellurian embracing and designed to illustrate the movements of the moon relative to both the sun and earth, the combination, with the moon-globe, of a hemispherical shield, supported and operated automatically by mechanism substantially as described.

JOHN A. BOWYER.
